Joseph B. Gardner
his ATTORNEY

Patented July 17, 1928.

UNITED STATES PATENT OFFICE.

JOSEPH DE VERRE, OF OAKLAND, CALIFORNIA.

APPARATUS FOR ELECTROPLATING AND THE LIKE.

Application filed January 26, 1923. Serial No. 614,975.

My invention relates to an apparatus for electroplating and the like in which the articles are treated in a container which is rotated in a tilted position.

5 An object of the invention is to provide an apparatus of the character described in which any container with its contents may be readily detached from or replaced on its mounting on the apparatus without stopping the operation of the apparatus as a whole or affecting the operation of similar containers remaining on the apparatus.

Another object of my invention is to provide an apparatus of the character described 15 having units adapted for efficient and economical arrangement and operation in multiple.

A still further object of this invention is to provide an apparatus of the character described which is simple and compact in structure and which reduces to a minimum the performance of manual assistance required in the performance of its functions.

The invention possesses other objects and 25 features of advantage, some of which, with the foregoing, will be set forth in the following description of the preferred form of my invention which is illustrated in the drawings accompanying and forming part 30 of the specification. It is to be understood that I do not limit myself to the showing made by the said drawings and description, as I may adopt variations of the preferred form within the scope of my invention as set forth in the claims.

35 Referring to said drawings:

Figure 1 is a front view of the apparatus of my invention showing a plurality of units arranged as a battery for simultaneous operation, one of the containers being omitted 40 from its mounting.

Figure 2 is a side sectional view of one unit taken on the line 2—2 of Figure 1.

A large per cent of the commercial electroplating, particularly of small articles, is 45 done by immersing the articles to be plated in an electrolyte contained in a barrel or container which is usually rotated in a tilted position. The containers are usually adapted to be fixed on their supports in such manner that the operation of the entire machine must be stopped before a container may be

removed from the machine or operatively replaced thereon. However, in accordance with my invention the container may be 55 readily removed or replaced while the machine is in operation. This feature is particularly advantageous when the plating apparatus includes a battery of container units as, first, it insures a minimum interruption 60 in the continuity of operation; second it enables a ready exchange of containers so that not only can different plating be more readily effected but the different allied operations such as polishing and burnishing 65 can be done with the same unit; third, the possibility of using a driving mechanism common to all of the units.

Briefly expressed, the apparatus in its present form comprises a plurality of like 70 units associated for simultaneous operation. Each unit essentially includes a container removably mounted on a rotatable shaft which is in turn mounted to revolve about a drive shaft common to all of the units. 75 The mounting of the container on the driven shaft is such as to allow its ready removal or replacement on the shaft during the operation of the apparatus, while the revolvable mounting of the driven shaft allows the 80 container to be rotated in any desired tilted position. Means are included for automatically maintaining the necessary electrical connections for a plating operation regardless of changes in position of the various 85 associated members of the apparatus.

A detailed description follows:

As illustrated in the drawings, the apparatus 3 includes a plurality of units 4 each of which comprises a container or barrel 5 with 90 rotatable and tiltable supporting means 7 and electrical connections for plating. The supporting means 7 as here shown includes a frame 8 having bearings 9 by which the frame is revolubly held on a main drive 95 shaft 12 suitably supported in bearings 10. Rotatably mounted in bearings 13 which are secured on the frame, is a driven shaft 14 having a bevel gear 16 fixed on one end thereof and meshing with a complementary 100 bevel gear 17 fixed on the drive shaft. Each of the driven shafts 14 is held against longitudinal displacement in either direction by collars 18 and 19 suitably held thereon.

The container is arranged to be removably mounted on the outer end 21 of the shaft 14, and partly for this purpose is provided with a flanged sleeve 22 which is attached to and extends from the bottom 23 of the container and is adapted for slidable engagement with the shaft.

Cooperative means are provided on the shaft 14 and the sleeve 22 for causing the container to become fixed for rotation with the drive shaft, or released from such engagement, by longitudinal displacement of the container on the shaft. In the present embodiment of the invention, this engagement and disengagement are respectively effected by the longitudinal displacement of the container on the driven shaft during the completion of the operation of mounting the former on the latter, and at the commencement of the container dismounting operation. In accordance with the foregoing the outer end portion 21 of the driven shaft is provided with one or more pins or teeth 24 set transversely therein and which may be readily engaged with or disengaged from the recessed extremity 26 of the sleeve upon a slight longitudinal displacement of the container, thereby causing the latter to be positively fixed for or released from rotation with the shaft 14. It is thus clear that by merely slipping the sleeve on or off the shaft the container may be operatively mounted thereon or readily released therefrom.

Due to the use of a single drive shaft, all of the shafts 14 during the operation of the machine are caused to be driven continuously and simultaneously, but on account of the method of connection between the container and the driven shaft, any one of the containers may be removed, replaced, or exchanged independently of the others at any time during such operation without any difficulty.

As previously explained, the frame is revolvably mounted on the drive shaft thereby allowing it to be moved through a vertical plane. This enables the container to be rotated while in various tilted positions, variations of the amount of tilt being permitted by lengthening or shortening the section of the chain 27 held between the hooks 28 and 29 which are fixed to said frame and wall 31 respectively.

Each container has arranged thereon a cathode 32 which is connected electrically with the sleeve by means of bolts 33 passing through the insulating material of which the walls of the container are preferably made. Current is conducted to the sleeve from the lead 34 by means of the shaft 14 and branch 36, the latter being held in proper electrical contact with the shaft by a brush 37. A spring 38 serves to hold the brush firmly pressed against the shaft during the

rotation thereof and regardless of the amount of the tilt of the frame.

The anode 39 which is connected to a lead 41 by a branch 42 is preferably suspended from an adjustable arm 43, the branch conductor 42 being fixed to the arm so that the anode may be held in the electrolyte with which the container is partially filled. A trough 44 is provided on the wall 31 in which the anode may be conveniently placed when not in use.

The apparatus may be driven by any suitable motive power properly connected with the drive shaft 12.

It is to be noted that while the apparatus in the present embodiment of the invention is made up of a plurality of units, a single unit incorporating many of the features of my invention may be used to considerable advantage.

I claim:

1. In an apparatus of the character described, a plurality of rotatable members pivoted to be swung in vertical planes, means for driving said members simultaneously, and containers arranged to be so mounted on said members that each may be removed from or replaced on said members while each of said members is rotating at normal speeds.

2. In an apparatus of the character described, a drive shaft, a plurality of shafts angularly disposed with respect to and arranged to be driven by said drive shaft, driving connections between said drive and driven shafts, frames revolvably mounted on said drive shaft independent of one another and arranged to rotatably support said driven shafts, means for adjustably holding said frames in position, containers adapted to be mounted on said driven shafts for rotation therewith and arranged to have an anode and cathode associated therewith, a clutch mechanism operable by the relative longitudinal displacement of a container and shaft to connect them for or release them from rotative engagement, an anode supporting member, and means arranged to hold the cathode electrically connected to a source of current in the various positions of and during the rotation of said driven shafts.

3. In an apparatus of the character described, a horizontal drive shaft, a plurality of shafts arranged at right angles thereto and adapted to be driven simultaneously thereby, bevel gears connecting each of said driven shafts to the drive shaft, frames revolvably mounted on said drive shaft independent of one another and arranged to support said driven shafts for rotation, means for holding said frames in adjusted position, containers removably mounted on said driven shafts for rotative and revolute movement therewith and arranged to be displaced from operative engagement there-

with during the rotation thereof at normal speeds.

4. In an apparatus of the character described, a plurality of rotatable members, 5 and containers arranged to be mounted on said member for rotation therewith that they may be readily removed from or replaced on said members while said members are rotating.
- 10 5. In an apparatus of the character described, a rotatable plurality of supports, containers adapted to be mounted on said supports for rotation therewith and arranged to have anode and cathode members 15 associated therewith, means operable entirely by and upon a relative displacement of said containers and supports to connect them for or release them from rotative engagement, and means arranged to

hold one of said members connected to a 20 source of current during the rotation of its support.

6. In a mounting for a tumbler barrel or the like, a revoluble shaft member arranged to be continuously rotated and having a free 25 upper end, a container arranged to be supported by and upon said shaft end, a sleeve member depending from said container and engageable about said shaft end, and co-operating clutch means on said shaft and 30 sleeve comprising a member projecting radially from the shaft and engageable in an axially directed recess provided in the extremity of the sleeve.

In testimony whereof, I have hereunto set 35 my hand, at Oakland, this 5th day of January, 1923.

JOSEPH DE VERRE.
